CENTERLESS GRINDER

William Ogilvie, Copt Heath, Knowle, England,
assignor to B. S. A. Tools Limited, Birmingham,
England, a British company

Application July 19, 1949, Serial No. 105,585
In Great Britain July 24, 1948

5 Claims. (Cl. 51—103)

1

This invention relates to centreless grinders of the in-feed type, that is to say, the type in which the grinding wheel (or in some cases the regulating wheel) is moved into and out of engagement with the workpiece.

It has previously been proposed to employ cam mechanism in order to move the grinding wheel or the control wheel into and out of operative position in timed relationship with automatic feeding of the workpieces to the throat between the two wheels. Such arrangements are not suited to hand-feeding of the articles in the machine.

The primary object of this invention is to provide in a centreless grinder, employing an in-feed cam to control the distance apart of the grinding wheel and control wheel, novel means to transmit drive to the in-feed cam, automatic means to interrupt the drive to the in-feed cam when a work-piece has been ground, and manually operable means to re-engage the drive to the in-feed cam to enable another work-piece to be ground.

The invention will now be more particularly described with reference to the accompanying drawings in which:

Figure 1 is a diagrammatic plan view of a centreless grinding machine showing only the parts thereof necessary to illustrate the invention;

Figure 2 is a section taken on the lines A—A of Figure 1;

Figure 3 is a view of a detail.

A regulating wheel 1 is rotatably supported and driven in any convenient manner, not shown and a grinding wheel 2 is supported by a bracket 3 and is rotated by any convenient means, not shown. A workpiece support 4 is disposed in the throat between the regulating and grinding wheels and a workpiece 5 is shown resting on the support between the two wheels. The bracket 3 is provided with a nut 6 which engages a lead screw 7 supported at its one end in a bush 8 rigid with the frame of the machine. Secured to this end of the lead screw is a hand wheel 9 and also secured to the lead screw is an abutment sleeve 10 between which and the bush is located a compression spring 11 tending to urge the lead screw axially in a direction to increase the distance between the grinding wheel and the regulating wheel. The bracket 3 or parts secured thereto form a slide which is supported in any suitable slideway, not shown. The end of the lead screw remote from the hand wheel abuts a splined push rod 12 slidably supported in a splined bore 13 formed in the machine frame, and the

2

splined push rod is provided with a roller 14 which bears on a button 15 carried by a lever 16 mounted on a pivot pin 17 rigid with the machine frame. The end of the lever remote from its pivot axis is bifurcated to provide two arms between which is disposed a roller 18 mounted on a pin 19 secured at its ends in the arms. A compression spring 20 operates between the machine frame and the lever 16 to urge the roller 18 into contact with an in-feed cam 21 and this action is supplemented by the force exerted by the spring 11. The in-feed cam 21 is secured on the upper end of a sleeve 22, hereinafter called the cam sleeve, rotatably mounted in an arm 23 in the machine frame, and rotatably mounted within the sleeve is the upper end of a vertically disposed spindle 24 whose lower end is supported by an arm 25 of the machine frame and having keyed to its lower end a toothed pinion 26 meshing with a toothed wheel, not shown, continuously rotated by a motor when the machine is started. Secured by a pin 26 to the spindle is a ring 27 formed on its upper face with clutch or dog teeth 28 which are backed off or chamfered and are adapted to be engaged by similar clutch or dog teeth 29 formed on the lower face of a clutch sleeve 30 freely mounted so as to be slidably and rotatable on the spindle 24. The upper end of the clutch sleeve 30 is provided with two diametrically opposite dogs 31, only one of which is shown, and each slidably engages a gap 32 formed in the lower end of the cam sleeve 22 so as to provide a sliding coupling between the cam sleeve and clutch sleeve which will transmit rotary motion and enable relative sliding movement of the clutch sleeve relative to the cam sleeve. A coiled compression spring 33 surrounds the spindle and abuts at its upper end against a shoulder 34 rigid with the cam sleeve and at its lower end abuts against the clutch sleeve which is provided with a face cam 35 urged into contact by the spring 33 with a projection 36 when the mechanism is in the position as shown in Figure 2. The projection 36 is secured to a plunger 37 supported in a block 38 rigid with the machine frame and a compression spring 39 urges the projection towards the axis of the spindle 24. The plunger is provided with a peg 40 which engages a slot 41 in the block to limit movement of the plunger. The peg 40 is engaged by an arm 42 rigidly secured on a suitably supported rotatable rod 43 from which depends an arm 44 hingedly connected to one end of a link 45 whose other end is connected to an arm 46 depending from a shaft 47 rotatably mounted

in a boss 48 of the machine frame and having a manually operable lever 49 secured at its outer end. Secured to the shaft 47 by a pin 50 is a collar 51 formed with an abutment 52 and an arm 53 to the end of which is connected a tension spring 54 whose other end is anchored to a fixed bracket 55. Carried by a fixed housing 56 are two set screws 57 and 58 which co-operate with the abutment 52 to limit the movement of the handle 49.

The clutch sleeve 30 is also formed with a groove 59 which is of V-shaped cross-section and in the position shown in Figure 2 is engaged by a V-shaped nose 60 formed on a plunger rod 61 slidably mounted in the block 38 and urged towards the spindle 24 by a compression spring 62. The plunger 61 is provided with a peg 63 which engages a slot 64 formed in the block 38 to limit sliding movement of the plunger 61 and prevent rotational movement thereof.

The operation of the machine will now be described commencing with the parts in the positions as shown in the drawings. An unground workpiece 5 has been inserted by hand between the grinding and regulating wheels and, referring to Figure 1, the hand lever 49 is moved towards the right i. e. in a clockwise direction to start the grinding operation. The arm 42 is thereby moved in an anti-clockwise direction, as shown in Figure 2, to retract the plunger 37 against the action of the spring 39 so that the projection 36 is withdrawn from engagement with the face cam 35 and the clutch sleeve 30 is moved by the spring 33 downwardly on the spindle 24 until clutch teeth 29 engage the clutch teeth 28 on the ring 27. As before stated the pinion 26, spindle 24 and ring 27 are continuously rotating when the machine is started and therefore rotary motion is transmitted to the clutch sleeve 30 which, through the sliding coupling transmits rotary motion to the cam sleeve 22 and in-feed cam 21. At the commencement of this rotary motion the plunger 61 is moved against the action of its spring 62 so that the V-shaped nose 60 is disengaged from the groove 59 in the clutch sleeve and the nose rides on the periphery of the sleeve. The in-feed cam 21 rotates in an anti-clockwise direction as viewed in Figure 1 so that the lever 16 is moved about its pivot pin in a clockwise direction to transmit sliding movement to the lead screw 7 against the action of the spring 11. The nut 6 and bracket 3 move with the lead screw and the grinding wheel is gradually fed towards the regulating wheel to remove stock from the workpiece. During the early part of this movement the end of the projection 36 rides on the periphery of the clutch sleeve 30 and prior to the in-feed cam attaining the position shown in Figure 2 the projection is spring-urged towards the spindle so as to co-operate with the face cam 35. As the highest point of the face cam approaches the projection 36 the clutch sleeve 30 is caused to gradually slide along the spindle 24 until, when the in-feed cam 21 attains the position shown in Figure 1 the clutch teeth 29 are disengaged from the clutch teeth 28 whereby the drive to the in-feed cam is discontinued. In this position the highest point of the in-feed cam 21 is past the roller 18 which now engages the lowest point of the in-feed cam, the drive to which is discontinued as before described. This position of the in-feed cam is maintained by engagement of the V-shaped nose 60 with the groove 59 in the clutch sleeve 30.

Immediately prior to the in-feed cam attain-

ing the position of rest as shown in Figure 1 a cam 65 movable with the in-feed cam, has operated ejector mechanism, not shown, to remove the ground or finished workpiece from between the grinding and regulating wheels. An unground workpiece can now be fed by hand between the wheels and the grinding operation commenced by the lever 49 being rocked by the operator.

10 If it is desired that unground workpieces should be fed automatically to the throat between the grinding and regulating wheels, instead of by hand, the lever 49 is rocked in anti-clockwise direction, as viewed in Figure 3, to withdraw the projection 36 from the face cam 35 and the set screw 57 is adjusted to lock the abutment against the set screw 58. The cycle of operations is then continuous.

Having thus described my invention, what I claim as new and desire to secure by Letters Patent is:

1. A centreless grinding machine comprising a rotatable grinding wheel, a rotatable regulating wheel, a stationary workpiece support between the grinding and regulating wheels, a rotary in-feed cam to control the distance apart of the grinding wheel and regulating wheel, a clutch to transmit rotary motion to the in-feed cam, automatic means to disengage the clutch when a workpiece has been ground, and manually operable means to engage the clutch to enable another workpiece to be ground.

2. A centreless grinding machine comprising a rotatable grinding wheel and a cooperative regulating wheel, said wheels having their peripheries opposed and spaced apart and being relatively movable to vary the space between them, a stationary workpiece support in the space between the wheels, means including a rotary in-feed cam for relatively moving the wheels to reduce the distance apart of their peripheries, means including a clutch for transmitting rotary motion to the in-feed cam, means cooperative with said clutch to disengage it when the distance apart of the wheels has been reduced to a predetermined amount, and means operable manually and cooperative with said clutch disengaging means to cause engagement of the clutch for transmission of rotary motion to the in-feed cam.

3. A centreless grinding machine comprising a rotatable grinding wheel, a rotatable regulating wheel, a stationary workpiece support between the grinding and regulating wheels, a rotary in-feed cam to control the distance apart of the grinding wheel and regulating wheel, a clutch to transmit rotary motion to the in-feed cam, automatic means to disengage the clutch when a workpiece has been ground, a member adapted to be rotated only when the clutch is engaged and the in-feed cam is rotated, spring-loaded retaining means so associated with said member as to hold the in-feed cam stationary when the clutch is disengaged after a workpiece has been ground and until the clutch is re-engaged, and manually operable means to engage the clutch to enable another workpiece to be ground.

4. A centreless grinding machine comprising a rotatable grinding wheel, a rotatable regulating wheel, a stationary workpiece support between the grinding and regulating wheels, a rotary in-feed cam to control the distance apart of the grinding wheel and regulating wheel, a spindle adapted to be continuously driven and concentric with and rotatable relative to the in-feed

cam, a ring secured concentrically to the spindle and formed on one face with clutch teeth, a complementary clutch member slidably mounted on the spindle, a face cam provided on the slideable clutch member, a projection which is cooperative with the face cam to cause axial displacement of the face cam and the respective clutch member to effect opening of the clutch and which is movable out of engagement with the face cam to allow the clutch to close and transmit rotary motion to the in-feed cam, spring means to urge the slideable clutch member towards the other clutch member, a sliding coupling between the slideable clutch member and the in-feed cam to transmit rotary motion, and spring-loaded retaining means associated with a part adapted to be rotated only when the clutch members are engaged so as to hold the in-feed cam stationary after a workpiece has been ground and the clutch members are disengaged and until said members are re-engaged.

5. A centreless grinding machine comprising a rotatable grinding wheel, a rotatable regulating wheel, a stationary workpiece support between the grinding and regulating wheels, a rotary in-feed cam to control the distance apart of the grinding wheel and regulating wheel, a spindle adapted to be continuously driven and concentric with and rotatable relative to the in-feed cam, a ring secured concentrically to the spindle and formed on one face with clutch teeth, a complementary clutch member slidably mounted on the spindle, a face cam provided on the slideable clutch member, a projection which is cooperative with the face cam to cause axial displacement of the face cam and the respective clutch member to effect opening of the clutch and which is movable out of engagement with the face cam to allow the clutch to close and transmit rotary motion to the in-feed cam, spring means to urge the slideable clutch member towards the other clutch member, a sliding coupling between the slideable clutch member and the in-feed cam to transmit rotary motion, and spring-loaded retaining means associated with a part adapted to be rotated only when the clutch members are engaged so as to hold the in-feed cam stationary after a workpiece has been ground and the clutch members are disengaged and until said members are re-engaged.

able clutch member, a projection which is cooperative with the face cam to cause axial displacement of the face cam and the respective clutch member to effect opening of the clutch and which is movable out of engagement with the face cam to allow the clutch to close and transmit rotary motion to the in-feed cam, spring means to urge the slideable clutch member towards the other clutch member, a sliding coupling between the slideable clutch member and the in-feed cam to transmit rotary motion, the slideable clutch member having a recess formed therein, a plunger so arranged that it fully engages said recess when the clutch is open to hold the in-feed cam stationary, and spring means tending to urge the plunger into engagement with the recess, the recess and plunger being so shaped that rotation of the slideable clutch member causes disengagement of the plunger from the recess.
